UNITED STATES PATENT OFFICE.

ADOLPH F. LONK, OF CHICAGO, ILLINOIS.

CARPET-STIFFENER.

1,380,989.

Specification of Letters Patent. Patented June 7, 1921.

Application filed May 12, 1920. Serial No. 380,864.

To all whom it may concern:

Be it known that I, ADOLPH FRANK LONK, a citizen of the United States, residing at Chicago, in the county of Cook and State of Illinois, have invented certain new and useful Improvements in Carpet-Stiffeners, of which the following is a specification.

This invention relates to improvements in carpet attachments having novel means whereby the corners of a carpet or rug may be prevented from crimping or rolling as the result of continued use.

An important object of this invention is to provide a carpet stiffener in the form of a flat metallic body adapted to be applied to one corner of a carpet for preventing the same from rolling or crimping as the result of being kicked over by the feet.

A further object of this invention is to provide a device of the class described which is easy to apply, efficient in use and cheap to manufacture.

Other objects and advantages of the invention will be apparent during the course of the following description.

In the accompanying drawing forming a part of this application and in which like numerals are employed to designate like parts throughout the same,

Figure 1 is a perspective of a rug or carpet having the corners thereof provided with the improved carpet stiffener.

Fig 2 is a fragmentary bottom plan view of a carpet or rug having the improved stiffener.

Fig. 3 is a detail section taken on line 3—3 of Fig. 2.

In the drawing wherein for the purpose of illustration is shown a preferred embodiment of the invention, the numeral 5 generally designates a rug or carpet which is adapted to be applied to the floor as a covering for the same. As is well known, the corners of a rug if not tacked to the floor soon turn over or roll as the result of being kicked by the feet so that the appearance of the rug is soon detracted from.

To overcome this disadvantage, I have conceived a means whereby the corners of the carpet may be prevented from rolling over or crimping upon being kicked by the feet or crimping by the movement of the furniture over the rug.

The improved carpet stiffener forming the subject matter of this application comprises

a flat metallic body 6 of elongated formation and which is adapted to be arranged beneath one of the corners of the rug so that when the corner of the rug is engaged by the feet or by the legs of a piece of furniture, 60 crimping or rolling of the rug will be prevented. As illustrated in Fig. 2, the flat metallic body 6 is provided with an attaching device 10 adapted to be detachably engaged with a rectangular loop 12 secured to the 65 under side of the carpet by stitching or other suitable means 14. The attaching device 10 is in the form of a tongue formed integral with the body and bent upon the body so as to form a socket 16 within which one side 70 or arm of the rectangular loop 12 is adapted to be detachably received. The forward portion of the tongue 10 engages a struck up shoulder or notch 18 formed in the body and coöperating with the outwardly curved 75 end portion of the tongue in forming a gradually restricted entrance opening or guide-way 20 for the loop.

The loop 12 is adapted to be permanently secured to one corner of the carpet or rug 80 so that when desired the flat metallic body 6 may be detachably connected to the same through the medium of the attaching device 10. By moving the device along the free side of the loop, the latter is directed through 85 the gradually restricted entrance opening 20 into the socket 16 so as to provide a secure connection between the stiffening body and the loop. When it is desired to remove the stiffening body from the rug or carpet for 90 the purpose of cleaning the same, it is merely necessary to disengage the free side of the loop from the attaching device 10. It will be noted that the struck up notch or shoulder 18 in the stiffening body 6 prevents the accidental disconnection of the rectangular loop 95 from the stiffening body since the struck up shoulder forms a rigid abutment over which the rectangular loop must pass upon being disconnected from the body.

With reference to the foregoing description taken in connection with the accompanying drawing, it will be observed that a carpet stiffener constructed in accordance with this invention may be readily and conveniently applied to rugs or carpets so that the necessity of tacking or otherwise securing the rugs to the floor is eliminated. While securing the rug or carpet against rolling, the device permits the rug or carpet 110

to be conveniently moved along the floor when it is desired to change the location of the same.

The rear portion of the body 6 is enlarged laterally so that the same is caused to be flatly engaged with the floor.

Having thus described the invention, what is claimed as new is:

1. A device for stiffening the corner of a carpet comprising an elongated body adapted to be arranged beneath a carpet and extended diagonally of the same, and an attaching member adapted to be permanently

secured to the corner of the carpet, said body being provided with means whereby the same 15 may be detachably connected to said attaching member.

2. A carpet stiffener comprising a flat metallic body having one end portion provided with an attaching device, and a loop 20 adapted to be permanently secured to a carpet and also adapted to be engaged by said attaching device.

In testimony whereof I affix my signature.

ADOLPH F. LONK. [L. S.]
